UNITED STATES PATENT OFFICE

2,512,121

TALKING MACHINE WITH RECORD CHANGER

Louis Thévenaz, Les Rasses, near Sainte-Croix, Switzerland, assignor to Hermann Thorens Societe Anonyme, a Swiss firm.

Application March 3, 1947, Serial No. 732,001
In Switzerland March 13, 1946

12 Claims. (Cl. 274—10)

1

This invention relates to talking machines with record-changer adapted to play automatically and successively the underside of the lowermost record of a stack supported on a first supporting surface and the upper side of the same record after it has been brought without reversal onto a second supporting surface positioned in vertical alignment with the first supporting surface.

An important feature of the invention resides in the provision of a single tone arm, at the extremity of which a pick-up with single oscillating device is pivotally mounted, and of means controlled by the cycle control device of the record-changer for turning said pick-up over by 180° in order to automatically bring the single stylus into either of the playing positions.

Other features and objects of the invention will appear hereinafter.

In the accompanying drawings in which are shown two practical embodiments of the invention:

Fig. 1 is an elevational view with parts in section of a first talking machine with record-changer embodying the invention, without casing and without device controlling the rotation of the pick-up with respect to the tone arm.

Fig. 2 is an enlarged broken view partly in section and partly in elevation of the central shafts of the machine.

Figs. 3, 4 and 5 are broken and enlarged axial sectional views of the record supporting shaft of the machine in three different working positions.

Fig. 6 is a cross-sectional view taken on line VI—VI of Fig. 3.

Fig. 7 is an elevational view with parts in section of the mechanism controlling the movements of the tone arm.

Fig. 8 is a general plan view of the mechanism controlling the movements of the pick-up and the record feeding.

Fig. 9 is a vertical sectional view taken on the broken line IX—IX of Fig. 8.

Fig. 10 is a plan view of the mechanism positioning the tone arm for playing different sized records.

Figs. 11 and 12 are partial elevational views of the mechanism positioning the tone arm for playing different sized records in two different working positions.

Fig. 13 is an elevational view of the cam controlling the movements of the tone arm.

Fig. 14 is a diagrammatic view illustrating the action of the cam shown in Fig. 13.

Fig. 30 is a sectional view taken on line XXX—XXX of Fig. 26; and

Fig. 31 is a top plan view of the device controlling the turning of the pick-up.

55 The first talking machine represented in Figs. 1

to 18 comprises a first electric motor 1 fixed to the underside of the base plate 2 by means of three bolts 3; the driving shaft 4 of this first motor rotates the turntable 5 on which is supported a 30 cm. record 6 the upper side of which is to be played by the pick-up 7 through the medium of its single stylus 8. The upper end of the driving shaft 4 is formed with a socket 9 within which is lodged a ball thrust bearing 37 rotatably supporting the semi-spherical lower end 10 of a straight shaft 11 extending vertically through the central aperture of a stack of records 12, the lowermost one 12¹ of which is supported on the supporting surface 13 formed by the upper edge of a U-shaped piece 34 (see Figs. 2 to 6) hingedly connected to the shaft 11, within a longitudinal groove thereof.

The semi-spherical upper end 38 of the shaft 11 is engaged in a bushing 14 formed at the lower end of the downwardly extending driving shaft 15 of a second electric motor 16 positioned above the stack of records 12 on a bracket 17 secured to the base plate 2 by means of feet 18 screwed thereto. On the stacked records 12 rests a presser plate 19 loosely engaging the shaft 11 and adapted to prevent the records from oscillating during their rotation. The upper motor 16 rotates in opposite direction to the lower motor 1 thus rotating the shaft 11, which is coupled with the driving shaft 15, and with shaft 11 the stacked records 12 in the opposite direction to the record 6 supported on the turntable 5.

Record feeding mechanism

As shown in Figures 2 to 6, the removable shaft 11 which rotates the stacked records 12 in opposite direction to the record 6 supported on the turntable 5 is hollow and within said shaft is slidably mounted a plunger 26 placed under the action of a coil spring 27 which tends to urge it upwards. At the lower end of the plunger 26 is secured a link 28 having a longitudinal slot 29 and a cross-pin 30. With the link 28 is hingedly connected a push-lever 31 pivoted at its upper end about a cross-pin 32 engaging the slot 29 of the link 28 and secured to the shaft 11; the push-lever is provided at its median portion with a biased slot 31a in which engages the pin 30 of the link 28 and is formed with a nose 31a. The push-lever 31 is thus hingedly connected with the link 28 in the fashion of a scissors blade so that a downward displacement of the plunger 26 against the action of the spring 27 causes the nose 31a of the push-lever 31 to emerge from the hollow shaft 11 above the supporting surface 13. The nose 31a has a thickness approximately equal to the thickness of the thinnest standard record and is thus adapted to push the lowermost record 12¹ of the stack laterally clear of the supporting surface 13 in order to cause it to drop by gravity along the lower portion of the shaft 11 onto the turntable 5, when, under the action of the record feeding device which will hereinafter be described the plunger 26 is displaced downwards. Meanwhile the upper edge of the nose 31a holds the last record but one 12² and the whole stack while the edge of the central aperture of the record 12¹ opposite to that which has been pushed by the nose 31a enters a notch 33 provided in the wall of the hollow shaft 11 so that said record 12¹ gets clear of the supporting surface 13 and drops onto the turntable 5. Fig. 3 shows the position of the record releasing members of the shaft 11 during the playing of a record, and Fig. 6 shows the same members in releasing position of the record 12¹.

The supporting surface 13 is formed by the upper edge of the U-shaped piece 34 which is hinged about a pin 35 diametrically crossing the hollow shaft 11. The piece 34 is placed under the action of a spring 36 which tends to maintain it in the position shown in the Figures 3 and 4 with the supporting surface 13 emerging from the shaft 11. The supporting surface 13 is thus collapsible into the inside of the hollow shaft 11 under the action of one or more records displaced upwardly as shown by the arrow f in Fig. 5. It is thus possible to restore at will one or more records from the turntable up to the supporting surface 13, which means to reload the changer without removing the shaft 11 and without waiting for all of the stacked records being played. During the reloading operation of one or more records, the notch 33 of the shaft 11 is obstructed by the lower end of the push-lever 31 so as to prevent the records from running against the shoulder formed by the upper edge of this notch.

The shaft 11 is rotatably supported by its lower semi-spherical end 10 on the ball thrust bearing 37 within the socket 9 and engaged by its semi-spherical upper end 38 in the bushing 14 formed at the lower extremity of the driving shaft 15 of the upper motor 16. The driving shaft 15 rotates at 78 revolutions per minute, like the driving shaft 4 of the lower motor 1, but in the opposite direction. It is driven by means of a worm gear 39, made of antisound material, meshing with a worm 40 formed at the extremity of the rotor shaft of the motor 16. The upper portion of the shaft 11 is provided with a longitudinal groove 41 in which engages a blade 42 riveted to a semi-circular spring 43 lodged in an annular groove of the bushing 14. The removable shaft 11 is thus driven by the blade 42 which is dependent upon the bushing 14, the latter being rigid with the driving shaft 15. The presser plate rotates together with the shaft 11. The lower end of the longitudinal groove 41 serves to hold the presser plate 19 when all of the stacked records have been released from the supporting surface 13.

The upper driving shaft 15 is axially bored and in its bore is slidably mounted a rod 44 the upper end of which emerges from the shaft 15 and is formed with a head 45 on which acts a bell crank lever 46 being part of the record feeding control mechanism which will hereinafter be described.

When it is desired to reload the changer, the shaft 11 carrying the presser plate 19 is removed by lifting it vertically until its lower semi-spherical end 10 is released from the socket 9 of the lower driving shaft 4, then inclining and lowering it to disengage its upper semi-spherical end 38 from the bushing 14. The different sized records to be played are then stacked in any desired order onto the turntable 5 with their central bore engaging the upper end of the shaft 4. The shaft 11 carrying the presser plate 19 is then restored to its axial position between the socket 9 and the bushing 14 and the whole stack of records is lifted manually along the shaft 11 causing the supporting surface 13 to collapse as shown in Fig. 5 against the action of the spring 36 which restores it after the passage of the lowermost record to its supporting position.

If, when the upper semi-spherical end 38 of the shaft 11 is introduced into the bushing 14, the coupling blade 42 does not lie in front of the groove 41, the spring 43 will yield up and permit introduction of the shaft, which then needs only

to be turned until the blade 42 enters the groove 41.

The record feeding control mechanism which actuates the plunger 26 through the medium of the rod 44 and of the bell crank lever 46 is shown in the Figures 1, 8, 9 and 10.

At the end of the playing of the underside of the lowermost record 12¹ of the stack, the stylus 8 of the pick-up enters the eccentric terminal groove of the records which imparts to the tone arm the sudden impulse which is necessary to couple the record feeding control mechanism with the lower driving shaft 4.

On the driving shaft 4 of the lower motor 1 is fixed a pinion 47 with which may be thrown into gear a coupling pinion 48 which constantly meshes with a large diameter gear 49 fixed on a shaft 50 on which is further fixed a cam 51 constituting the tone arm cycle control member. This cam 51 is held at rest during the playing of a record side, but is rotated by the driving shaft 4 from the end of the playing of this record side to the beginning of the playing of the successive record side. The coupling pinion 48 is loosely mounted on a shaft 52 secured to the under side of a lever 53 pivoted about a pin 54 secured to the under side of a plate 55 and placed under influence of a restoring spring 59. The lever 53 carries further on its upper side, a pin 56 adapted to co-operate through a hole of the plate 55 with a stop surface 57 of a bell crank 57 pivoted about a pin 58 secured to the plate 55. The large diameter gear 49 is fixed on the shaft 50 by means of a pin 60 passing through a sleeve 61.

The lever 53, swingingly arranged so that its coupling pinion 12 meshes constantly with the gear 49 and may be engaged with or disengaged from the pinion 47 according to the position of the bell crank 57. When the pinion 48 meshes with the pinion 47, the movement of the driving shaft 4 is transmitted at reduced speed by the gear 49 to the cam 51 which comprises all the necessary elements to control the movements of the single tone arm. The position of the bell crank 57 is controlled by a lever (not shown) connected with the tone arm.

From the gear 49, the rotary motion is transmitted to a gear 62 fixed on the shaft 63 of a pinion 64. This pinion meshes with a gear 65 secured to a sleeve 66 loosely mounted on a bushing 67 secured to a lower plate 68. Both the plates 55 and 68 which constitute the frame of the mechanism are secured together to the base plate 2 of the machine by means of three bolts 69. The gear ratio is such that the gear 65 is moved one half of a revolution while the large diameter gear 49 is moved one complete revolution.

In the fixed bushing 67 is pivotally mounted a shaft 70 on the lower extremity of which is fixed a second cam 71 which constitutes at the same time the control member of the record feeding and the member controlling the positioning of the pick-up according to the size of the record to be played. On the upper extremity of the shaft 70 is mounted a coupling sleeve 73 secured to the shaft 70 by a screw 74. The coupling sleeve 73 is adapted to be connected with the sleeve 66 of the gear 65 through the medium of a semi-circular coupling lever 75.

The coupling lever 75 is pivoted about a pin 76 secured to the gear 65 as shown in Fig. 10. A coil spring 77 attached to a lug 78 of the gear 65 draws the extremity 75 of the lever 75 to cause a bent lug 79 of the lever 75 to engage one of the diametrically opposite notches 80 of the sleeve 73.

thus transmitting the movement of the gear 65 to the cam 71. The sleeve 66 is provided with a countersink for the passage of the lug 79 of the lever 75.

The cam 71 is provided with two different cam paths 82 and 83 arranged diametrically opposite to one another and of different radius. The cam path 82 constitutes the control member of the record feeding and the cam path 83 constitutes the control member of the record size detection.

Cam path 82 co-operates with a roller 84 pivoted about a pin 85 secured to a bell crank 86. Bell crank 86 is pivoted by a sleeve 86' secured to its extremity about a shaft 87 fixed to a bracket 88 secured by a screw 89 to the underside of the base plate 2 of the machine. With another extremity of the bell crank 86 is hingedly connected, by a means of a pin 90, a sleeve 91 having a slot 92. The sleeve 91 is provided with an inner thread in which is screwed the screw threaded lower end of a rod 93. A coil spring 94 bearing against the underside of the base plate 2 acts on the sleeve 91 and tends to push it, together with the rod 93, downwards. The rod 93 passes through an aperture of the base plate 2 and its screw threaded upper end 93' is screwed in a sleeve 95 pivoted about a pin 96 secured to outer end of the bell crank lever 46 pivoted about a pin 97 fixed to a lug 98 of the bracket 17 on which is secured the upper motor 16.

When at the end of the playing of the underside of the record 12¹, the stylus 8 enters the eccentric terminal groove of this record, the sudden impulse imparted to the tone arm puts into action the automatic stop device and causes the coupling pinion 48 to engage with the pinion 47 of the driving shaft 4. The rotation of the gear 49 is then transmitted to the cam 71 which begins to rotate. The roller 84 cooperating with the cam path 82 lifts the bell crank 86 and the rod 93; the lever 46 is rotated about the pin 97 and its inner extremity presses against the head 45 of the rod 44 which latter is moved downwards through the hollow shaft of the upper motor 16 and presses against the upper end of the plunger 26; the plunger is thus moved downwards and rotates the push lever 31 within the removable shaft 11, thus causing the nose 31a to displace laterally the lowermost record 12¹ of the stack to get it clear of the supporting surface 13.

It is to be remembered that the cam 71 is moved one half of a revolution while the cam 51 controlling the movements of the tone arm is moved one complete revolution with the result that the record feeding device operates one time while the cam 51 is moved two revolutions; that is to say after the playing of both the sides of the record 12¹.

Record size detection mechanism

The record size detection mechanism, that is the mechanism for positioning the single tone arm according to the size of the record to be played, comprises a first lever 99, pivoted about the same shaft 87 about which is pivoted the bell crank 86 of the record feeding mechanism, and a second lever 100 pivoted at the upper extremity of the first lever 99 about a pin 101. At the free end of the second lever 100 is mounted a roller 104 pivoted about a pin 102 fastened by its flat shank 103 to the end of the lever 100. The first lever is controlled by the cam path 83 of the cam 71 with which co-operates a roller 105 pivoted about a pin 106 carried by the extremity of a bell crank 107 pivoted about the shaft 87 and resiliently connected with the lever 99 by a coil

spring 108; coil spring 108 is attached at the one extremity to a lug 109 of the bell crank 107 and at the other extremity to a lug 110 of lever 99. This resilient connection between lever 99 and bell crank 107 enables lever 99 to effect a variable stroke according to the roller 104 running or not against the edge of a 25 cm. record, while bell crank 107 is effecting an invariable stroke under influence of the cam path 83 of cam 71. The levers 99 and 100 are also resiliently connected by means of a second coil spring 111 attached at one end to a lug 112 of lever 100 and at the other end to a lug 113 of lever 99. This second spring is intended to hold the roller 104 in contact with the lowermost record 121 of the stack, even if this record oscillates while rotating.

The feeler device comprising the levers 99 and 100 and the springs 108 and 111 is arranged so that if the record 121 is a 30 cm. record (Fig. 11) the roller 104 rolls, in working position of the feeler, on the underside of the record, at a distance X from the axis of the records less than 25 cm., and if this record 121 is a 25 cm. record (Fig. 12) the said roller 104 runs against the edge of said record, that is to say at a distance $X + x$ from the axis of the records; in the latter case the springs 108 and 111 tend to bring the roller 104, during the inward motion of the lever 100 under the influence of the cam path 83, to a higher level than the underside of the record 121.

At the beginning of the cycle the feeler occupies the position indicated in dotted lines in the Figure 11, in which position the roller 104 is positioned beyond the periphery of the largest record of the stack; in this position it does not hinder the records from dropping into the turntable. Under the action of the cam path 83, the bell crank 107 carrying the roller 105 rotates about the shaft 87 and drives, through the medium of the spring 108 the lever 99 in the counterclockwise direction, as shown in Fig. 12. If the record 121 is a 30 cm. record, the roller 104 performs a travel A-B-C in order to come to roll on the underside of this record 121 as shown in Fig. 11, at the distance X from the axis of the records. The lower extremity 99' of lever 99 comes to occupy a position Y^1 .

If however the record 121 is a 25 cm. record (Fig. 12) the roller 104 comes to run against the edge of this record, thus performing a travel A-B' equal to A-B. The lower extremity 99' of lever 99 comes to occupy a position Y^2 . The difference between the positions Y^1 (Fig. 11) and Y^2 (Fig. 12) permits, by means of a lever system shown in Fig. 8 and described hereinafter, to determine the initial playing position of the pick-up so that its stylus comes to lie exactly in alignment with the beginning of the outer groove of the record 121 whether this record is a 30 cm. or a 25 cm. one.

The Fig. 8 shows, in sectional view, the pivoting of the lever 99 about the pin 87. The lever 99 is riveted on a sleeve 114 pivoted about the shaft 87 on which are also pivoted the sleeve 86' of the record feeding lever 86, and the bell crank 107. The whole is axially held in place between a shoulder 115 formed at the one extremity of the pin 87 and the extremity 116 of the bracket 88 to which the shaft 87 is secured by means of a pin 117.

The extremity 99' of lever 99 is positioned on the way of the extremity 118' of a lever 118 pivoted about a pin 119 secured to the lower plate 68 of the mechanism frame; lever 118 is bent at 120 and provided with a projection 121 placed

on the way of a projection 122 on the periphery of the cam 71. At its opposite extremity, the lever 118 has two stair-like contact surfaces; namely the surface 123 which is the more distant, and the surface 124 which is the less distant from the pin 119. Both the surfaces 123 and 124 are intended to co-operate, according to the position of the lever 118, with an arm 125 being part of the mechanism controlling the movements 10 of the tone arm. The extremity 118' of lever 118 may be brought into three different positions: (a) under the action of the peripheric projection 122 of the cam 71 on the projection 121, it is moved to the extreme left positions; (b) if the 15 roller 104 of the feeler runs against the edge of a 25 cm. record (Fig. 12), the extremity 99' of lever 99 being in the position Y^2 moves the extremity 118' of lever 118 into its middle position shown in Fig. 8. The arm 125 is then positioned in front to the contact step 124 of the lever 118; (c) if the roller 104 rolls on the underside of a 30 cm. record as shown in Fig. 11, the extremity 99' of lever 99 being in the position Y^1 moves the extremity 118' of lever 118 into its 20 extreme right position in which the arm 125 co-operates with the contact step 123.

Pick-up control mechanism

The sound reproducer comprises a single tone arm 20 carrying a single pick-up 7 adapted to play successively the underside of the record 121 of the stack supported on the supporting surface 13 of the removable shaft 11, and the upper side of the record 6 supported on the turntable 5. The tone arm 20 is pivoted about a horizontal shaft 21 positioned below the upper surface of the turntable 5. The pick-up 7 carries a single stylus 8 fixed by the screw 23 (Fig. 7) in an oscillating stylus holder armature, and comprises a device of any known kind (not shown) for transforming the mechanical oscillations of the stylus and of the armature into electromagnetic oscillations. The pick-up 7 comprises a box to which is rigidly secured a shaft 22 rotatably supported in a cylindrical recess 24 provided in the extremity of the tone arm 20, (Figs. 16, 17, 18). The point of a screw 25, screwed in the tone arm 20 engages a circular groove 22' of the shaft 22 thus allowing rotation of said shaft while securing it against any axial displacement. Balls 196 and 197 placed under the action of coil springs 198, 199, are adapted to partly enter two pockets 200, 201 provided in the outer front face of a ring 202 secured to the shaft 22 by a screw 203 and adapted to be turned when said screw is unscrewed. The balls 196, 197 cooperating with the pockets 200, 201 determine two definite angular positions of the pick-up 7 with respect to the tone arm 20: namely the position 7' (Fig. 16) in which the stylus 8 is turned downwardly, and the position 7'', in which the stylus is turned upwardly (position 8'); the pick-up passes from one to the other position by a rotation about 180° of the shaft 22 with respect to the tone arm 20. These positions may be adjusted by turning the ring 202 about the shaft 22.

The reversal of the pick-up 7 with respect to the tone arm 20 is brought about by a device comprising a housing 204 secured to the base 70 plate 2 of the talking machine by two screws 205^a, 205^b (Fig. 18) in such a position that when the tone arm 20 occupies the position of rest shown in Fig. 8, beyond the periphery of the records supported on the turntable and on the shaft 11, a horn 206 secured to the box of the

pick-up 7 enters a recess 207 of a cylindrical piece 207 formed rigid with a shaft 208 rotatably supported in two bearings 209, 210 formed rigid with and secured to the housing 204 respectively. A pinion 211 is fixed on the shaft 208 by a pin 212; this pinion is also intended to hold the shaft 208 against any axial displacement with respect to the housing 204. A bevelled gear 213 fixed by a pin 214 to a vertical shaft 215 rotatably supported in two bearings 216, 217 being parts of the housing 214, meshes with the pinion 211. On its lower end, the vertical shaft 215 carries a sleeve 218 secured thereto by a pin 219. On the front face of this sleeve 218 is riveted a lever controlled by a link 221 hingedly connected therewith by means of a rivet 220. At the opposite extremity of the link 221 is provided an elongated slot 223 in which is engaged for sliding movement a pin 224 secured to the cam 71.

During the playing of the underside of the record 121 supported by the supporting surface 13 of the removable shaft 11, the single pick-up 7 is positioned so that the stylus 8 follows the sound groove of this record (positions 7" of the pick-up and 8" of the stylus). At the termination of the playing of this underside of the record 121, the single tone arm 20 is brought back by a mechanism hereinafter described into the position of rest shown in Fig. 8, that is to say beyond the periphery of the largest record. The cam 71 which, as hereinbefore described, rotates in the direction of the arrow f², actuates by means of the pin 224 the link 221. The link 221 actuates the lever 220 and the latter rotates the vertical shaft 215 carrying the bevelled gear 213 which meshes with the pinion 211; the pinion 211 is thus driven in rotation, thus rotating the cylindrical piece 207 in the recess 207 of which is engaged the horn 206 of the pick-up 7. The elongated slot 223 of the link 221 is dimensioned so that while the cam 71 rotates a half of a revolution, the cylindrical piece 207 and thus the pick-up 7 is swung back about 180°. The stylus 8 is then positioned to play the upper face of the record 6 supported on the turntable 5.

After the termination of the playing of the record 6, the single tone arm 20 is brought back into its position of rest shown in Fig. 8. The cam 71 which performs at this time a travel through a half of a revolution in the direction of the arrow f², promotes through the medium of link 221, lever 220, shaft 215, gear 213, pinion 211 and piece 207, a new reversal of the pick-up 7 through 180° but in the opposite direction. The stylus 8 is then newly directed upwards for playing the underside of the lowermost record 122 of the stack.

The single tone arm 20 carrying the reversible pick-up 7 is controlled by means of the cam 51 which determines all of the movements thereof through the medium of two distinct cam paths with which co-operates at will a guiding pin 126 carried by a member connected with the tone arm.

The cam 51 secured to the vertical shaft 50, comprises on a portion of its periphery a single cam path 127 adapted to control the inward and outward movements of the tone arm before and after the playing of each record side. On another portion of its periphery, between the radii L and L' (Fig. 14), the cam 51 is provided with two cam paths 128 and 129 diverging at 130 from the cam path 127 and converging to the latter at 131. The guiding pin 126 may follow from 130 to 131 either the path 128 or the path 129

when the cam 51 rotates in the direction of the arrow f¹, in order to control the upward and downward movements, respectively, of the tone arm. At 130 a switch 132 pivoted about a pin 133 permits to turn off the guiding pin 126, at will into one or the other paths 128, 129. The control mechanism of this switch 132 will be hereinafter described. Both the paths 128 and 129 are situated on the outer surface of a common cylinder, the axis of which is the axis of the shaft 50. The path 128 comprises a rising ramp 128¹ followed by a descending ramp 128²; inversely the path 129 comprises first a descending ramp 129¹ followed by a rising ramp 129².

The guiding pin 126 which follows the grooved cam paths under the action of a spring 250, as shown in Fig. 8, is fixed to the one end of an arm 134 pivoted at its other end about a pin 135 riveted on the extremity of a second arm 136 adapted to turn about the horizontal pin 21 constituted by the opposite points of two cones 137, 138 engaged in lugs 139, 140 of the arm 136 and fixed in the lugs 141, 142 of a bracket 143 welded to the base plate 2. The cone 138 is adjustable by means of a screw threaded sleeve 144 and may be locked in position by a nut 145. At the upper end of the arm 136 is fixed by means of screws 146, 147 a piece 148 to which is welded a U-shaped piece 149 in the legs of which are bored conical holes in which are engaged the conical points 150, 151 of bolts 152, 153 screwed in lugs 154, 155 of a bracket 156. The cones 150, 151 constitute the vertical axis of rotation of the tone arm with its support. The bracket 156 carries itself a horizontal pin 157 about which the tone arm 20 is pivoted for vertical movements so that the pick-up may freely follow the vertical oscillations of the records independently from the upward and downward movements imparted thereto by the cam 51 before and after the playing of each record side and that the pick-up may also be lifted and lowered manually from its upper and lower playing positions respectively, without changing the position of its support, that is of the arms 136, 134 and guiding pin 126.

A spring leaf 158 fixed to the bracket 156 by a screw 159 serves to press the pick-up against the under side of the record 121 so as to provide it with the necessary pressure for playing this record side when the guiding pin 126 after having followed the cam path 128 thus rotating the levers 134 and 136 about the horizontal shaft 21 reaches to the top of the rising ramp 128¹ into the position 126' shown in dotted lines in Fig. 7. In the position of the pin 126 shown in full lines in Fig. 7, that is at the foot of the descending ramp 129¹ of the cam path 129, the downwardly directed stylus 8 of the pick-up plays the upper side of the record 6 supported on the turntable 5; the spring leaf 158 does not put any pressure on the tone arm; but it is through this same spring leaf that the arms 134 and 136 lift the tone arm over the record 6 after its upper side has been played, as the pin 126 follows the rising ramp 128² of the cam path 128.

A stop 160 fixed by screws 161, 162 to the bracket 156 limits the downward displacement of the tone arm about the horizontal pin 157.

The inward and outward displacements of the pick-up caused by the pin 126 following the path 127 of the cam 51 are transmitted to the tone arm support by the arm 134 pivoted about the vertical pin 135, through the medium of a link 163 pivoted too about 135 and of an other arm 164 fixed by the screws 161, 162 to the bracket

11

156 (Figs. 7 and 8). When the pin 126 travels through the first portion 127¹ (Fig. 8) of the cam path 127, while the cam 51 rotates in the direction of the arrow f^1 , the arm 134 is rotated about 135 in the clockwise direction. The edge 134¹ of this arm draws forth the link 163 by the lug 163¹ thereof. This link 163 is provided at its extremity opposite the pin 135 with a rectangular aperture 166, the edge 165¹ of which draws forth a pin 166 secured to the arm 164 fixed to the bracket 156 thus drawing the tone arm into rotation about the vertical axis 150—151 towards the outside of the turntable, until the horn 206 of the pick-up box enters the groove 207¹ of the device controlling the reversal of the pick-up.

When the pin 126 follows the portion 127² of the cam path 127, it draws the arm 134 together with the link 163 in counter-clockwise direction; it is then the edge 165² of the aperture 165 which draws forth the pin 166 and rotates the tone arm through the medium of the arm 164 towards the inside of the turntable. The inward movement of the tone arm proceeds until the arm 125 dependent upon the link 163 comes in contact with one of the steps 123 or 124 on the lever 118 of the record size detecting device. If it runs against the step 123, the pick-up will be stopped over the outer groove of a 30 cm. record; if however the arm 125 runs against the step 124 of the lever 118, the pick-up will be stopped in its inward movement over the outer groove of a 25 cm. record.

A spring 167 attached at the one end to the lug 163¹ and at the other end to a lug 168 of the arm 134 tends to maintain the edge 134¹ of this arm in contact with the lug 163¹ of the link 163 and absorbs the stroke difference between these levers when the arm 125 comes to run against one of the steps 123 or 124, which occurs before the pin 125 reaches its outermost position on the cam path 127.

The pin 166 is turned eccentrically on a collar 188 of a pin 170 mounted with hard friction in a hole of the arm 164. This hard friction is obtained by means of a spring 171 tensioned by a washer 172 and a cross pin 173. By rotating the pin 170 it is thus possible to adjust the stop position of the pick-up above or under the outer groove of the record side to be played. 174 indicates a pin set in the arm 164 which serves to actuate the automatic stopping mechanism, not shown. The control of the switch 132 of the cam 51 is performed through the medium of the following device (Figs. 10, 13 and 15):

On the pin 133 of the switch 132 is fixed a lever 175 submitted to the action of a restoring spring 176 attached to a pin 177 on the cam 51. This lever 175 bears against an other lever 178 pivoted about 179. This latter lever 178 bears in its turn against a cam disc 180 pivoted about a screw 181 and rigidly connected by a pin 183 with a four-armed star wheel 182. The Figure 15 illustrates the detail of the revolving unit 180—182. At each revolution of the control cam 51, a pin 184 set in the extremity of a lever 185 pivoted about a pin 186 causes the star wheel to move one step thus rotating the cam disc 180 one fourth of a revolution. If thus the lever 178 occupies during one revolution of the cam 51 the position indicated in full lines in Fig. 10, during the following revolution, under influence of the cam disk 180 having moved the star wheel one fourth of a revolution, it will take an other position and its displacement will promote a corresponding displacement of the lever 175 dependent upon the switch 132; the latter changes thus its position

12

at each revolution of the cam 51 thus switching the pin 126 by turn onto either the path 128 or the path 129. If it is desired to repeat either the under side of the record 6 or the upper side of the record 6, it will be sufficient to retract the pin 184 from the way of the star wheel 182 by rotating the lever 185 to bring it into the position 185¹ shown in dotted lines in Fig. 10. The switch 132 will thus be maintained in its initial position during the subsequent revolution of the cam 51 and the tone arm will repeat the movements of the half-cycle just accomplished until the pin 184 will be brought back onto the way of the star wheel 182.

15 The repeating lever 185 is T-shaped and pivoted about the pin 186 secured to the upper side of the lower plate 68 of the mechanism. The extremity 187 of its cross arm opposite the pin 184 is situated, in the position shown in full lines in Fig. 10, out of the way of the coupling lever 75, and, in the position shown in dotted lines corresponding to the position 185¹, on the way of this coupling lever, thus disengaging it from the sleeve 73 and stopping the cam 71. Owing to the cam 71 being stopped, the mechanism controlling the reversal of the pick-up 7 remains unoperative and the stylus 8 remains in the position corresponding to the repetition of the record side which has been just played.

30 A lever 188 pivoted about a pin 189 on the lower plate 68 is also controlled by the lever 185 through the medium of a link 190 pivoted about a pin 191 on the arm 192 of the lever 185 and about a pin 193 on the lever 188. This lever system is so arranged that when the extremity 187 of the lever 185 is out of the way of the coupling lever 75, the lever 188 has its extremity 194 also out of this way and when 187 is on this way, 194 is there too. The repeating lever 185 is controlled by a knob 195 placed at the extremity of its middle arm 192. When this knob is pushed into the position 195¹, the pin 184 is brought out of the way of the star wheel 182 while 187 and 194 are brought into the way of the coupling lever 75, thus stopping the cam 71.

45 The function of the various mechanisms will be now described:

(a) *Playing cycle without repetition*

50 1. The terminal eccentric groove of the upper side of the record 6 supported on the turntable 5 imparts to the stylus 8 of the pick-up 7 a sudden impulse which is transmitted by the tone arm 20 through the arm 164 and the pin 174 to an automatic stopping device of a known type, not shown. This stopping device promotes the counter-clockwise rotation of the lever 57 which releases the pin 56 from the terminal notch thereof. The rocking lever 57 is rotated in a counter-clockwise direction about the pin 54 until the coupling pinion 48 comes into gear with the pinion 47. The cams 51 and 71 begin then to rotate in the direction of the arrows f^1 and f^2 .

55 2. The pin 126 which was positioned during the playing of the record 6 at the point A of the cam path 129, follows the rising ramp 129². The support of the tone arm is moved in a clockwise direction about the horizontal shaft 21 thus tensioning the spring 158 and lifting the pick-up 70 above the record 6. When the pin 136 reaches to the point B of the ramp 129², the pick-up is situated in a middle position, where the stylus 8 does not contact any record.

Meanwhile the pin 184 of the lever 185 has rotated the star wheel 182 one step, thus swinging

the switch 132 in a counter-clockwise direction; the switch 132 closes the inlet of the path 129 and opens the way into the path 128. During the playing of the upper side of the record 6 supported on the turntable, the switch 132 was closing the path 128 and opening the inlet of the path 129.

From the point B, the pin 126 follows the first portion 127¹ of the cam path 127 thus causing the arm 134 to rotate in a clockwise direction about 135. The pin 166 of the arm 164, which at the end of the record 6 was in the position 166' shown in dotted lines in Fig. 8, is drawn forth in a counter-clockwise direction by the edge 165¹ of the aperture 165. The arm 164 causes the tone arm to swing in a counter-clockwise direction about the vertical axis 150—151 thus bringing the pick-up out of the periphery of the largest record when the pin 126 reaches to the cusp C of the path 127 which is diametrically opposite the point A with respect to the shaft 50 of the cam 51.

3. Meanwhile, the cam 71 which controls the record size detection and the record feeding has been rotated one fourth of a revolution. The peripheric projection 122 has thrown back the part 121 of the lever 118, thus bringing the end 118' of this lever into its extreme left hand position. During the same fourth of a revolution of the cam 71, the path 83 of the cam promotes the necessary movements for the record size detection through the medium of roller 105, bell crank 107, levers 99 and 100 and roller 104. The lever 118 is brought into the position corresponding to the size of the lowermost record 12¹ of the stack supported on the surface 13 of the shaft 11.

As the cam 71 is further rotated, it draws forth, through the medium of the pin 224, the link 221 which, through the shafts 215 and 208 and the grooved piece 207 reverses the pick-up 7 about 180° in the counter-clockwise direction, whereby the stylus 8 is brought into position for playing the underside of the record 12¹.

4. As the cam 51 is further rotated, the pin 126 follows the second portion 127² of the path 127, thus causing the arm 134 and the link 163 to rotate about 135 in a counter-clockwise direction. The edge 165² of the aperture 165 throws back the pin 166 until the arm 125 dependent upon the link 163 comes into contact with either the steps 123 or 124 of the lever 118. The upward directed stylus 8 of the pick-up 7 is then positioned below and in alignment with the outer groove of the record 12¹, whatever the size of this record may be.

5. The pin 126, after having reached to the point D where lies the switch 132, follows the rising ramp 128¹ of the path 128, the inlet of which has been opened by the switch. The arm 134 draws forth the arm 136 about the horizontal shaft 21 in a clockwise direction. This rotation brings about the lifting of the tone arm which rests on the leaf spring 158. The stylus 8 enters the outer groove of the record 12¹; the contour of the ramp 128¹ is so conformed that after the stylus 8 has entered the groove of the record 12¹, the support of the tone arm is given a small increment of rotation about the horizontal shaft 21, so that the leaf spring 158 puts on the tone arm an upward pressure sufficient to secure the correct working of the pick-up.

6. At the end of the rising ramp 128¹, the cam 51 has accomplished one full revolution. The rocking lever 53 has been rotated in a clockwise direction about the pin 54 thus putting the cou-

pling pinion 48 out of gear from the pinion 47 and stopping the cam 51 together with the whole mechanism of the record changer. Meanwhile both the motors rotate further and the pick-up 7 plays the under side of the record 12¹ supported on the supporting surface 13 of the shaft 11.

7. The eccentric terminal groove of the record 12¹ actuates the automatic stopping device; the coupling of the record changing mechanism is brought about as above described and the cams 51 and 71 begin once more to rotate.

The pin 126 which was stopped at the point E, follows now the descending ramp 128² of the cam path 128 thus causing the arms 134 and 136 to rotate in a counter-clockwise about the horizontal shaft 21. At the foot of the ramp 128², the pin 126 has reached again the point B and the pick-up has been restored to its middle position between the records 12¹ and 6.

On its way, during this latter fourth of a revolution of the cam 51, the pin 184 of the lever 185 has moved the star wheel 182 one step. The switch 132 has been swung in a clockwise direction thus closing the cam path 128 which has just been passed through by the pin 126 and opening the cam path 129.

From the point B, the pin 126 follows once more the first portion 127¹ of the plane cam path 127 thus causing the arm 134 to rotate in a clockwise direction about 135. The pin 166 is drawn back in a counter-clockwise direction by the edge 165¹ of the aperture 165. The arm 164 causes the tone arm to rotate in a counter-clockwise direction about the vertical axis 150—151 and the pick-up is brought out of the periphery of the records; the horn 206 of the pick-up is once more engaged within the groove 207' of the cylindrical piece 207 of the device controlling the reversal of the pick-up.

8. Meanwhile, the cam 71 has been rotated a third fourth of a revolution. Its path 82 cooperating with the roller 84 causes the lever 86 to rotate in a counter-clockwise direction thus lifting the rod 93 and lowering the inner end of the bell crank 48 which presses on the head 45 of the rod 44; this rod actuates the plunger 26 which is lowered within the shaft 11 and actuates the piece 31, the nose 31a of which releases the record 12¹ from the supporting surface 13. The record 12¹, the under side of which has just been played, drops by gravity along the shaft 11 onto the record 6 which rests on the turntable 5.

As the cam 71 is further rotated, it draws back the link 221 which through the shafts 215 and 208 and the grooved piece 207 reverses the pick-up 7 about 180° in the clockwise direction, thus bringing the stylus 8 back into position for playing the upper side of the record 12¹ now supported on the record 6.

9. Now as the cam 51 is further rotated, the pin 126 follows the second portion 127² of the plane cam path 127, whereby the tone arm is brought back inwardly over the outer groove of the upper face of the record 12¹ resting now on the turntable. The lever 118 for the record size detection remains in the position occupied at the end of the cycle part above designated 3. The downward directed stylus 8 of the pick-up 7 is thus positioned exactly over the outer groove of the upper face of the record 12¹.

10. The pin 126 follows then the descending ramp 128¹ of the cam path 128 and comes back to the point A which it occupied at the beginning of the cycle described. This latter displacement

15

causes the arms 134 and 136 to rotate in a counter-clockwise direction about the horizontal shaft 24 thus lowering the pick-up to permit the stylus 8 to enter the outer groove of the upper side of the record 12¹ resting now on the record 6.

The mechanism of the record changer is then automatically disengaged and the pick-up plays the upper side of the record 12¹.

The cycle which has just been described comprised all of the necessary movements to play successively both the sides of the record 12¹ substantially without interruption and without turning this record over. The cam 51 has accomplished two full revolutions and the cam 71 one full revolution during which its path 83 has acted one time for effecting the detection of the size of the record 12¹ and the path 82 has acted one time for dropping this record 12¹ onto the turntable.

Concerning the size detection mechanism, it is to be pointed out that the position of the lever 118 which determines the starting position of the pick-up for playing either a 30 cm. or a 25 cm. record is independent from the absolute level of the edge of the record 12¹ when the latter rests on the supporting surface 13 of the shaft 11. The detection may thus be correctly brought about even if the edge of the record 12¹ oscillates vertically while rotating or if it is not exactly circular.

(b) *Playing cycle with repetition*

First case.—Repetition of the upper side of the record 6 supported on the turntable 5. The cycle is at the point above designated 1. The pin 126 follows the rising ramp 129² of the cam path 129. The repeating lever (192—185—187) is brought into the position shown in dotted lines in Fig. 10, in which position the pin 184 lies out of the way of the star wheel 182. This star wheel being no more actuated by the pin 184, the switch 132 remains thus in the same position, closing the path 128 and taking open the path 129 which has been just passed through by the pin 126. Furthermore, the extremity 194 of the lever 188 comes to bear against the coupling lever 75 thus causing the latter to rotate in a counter-clockwise direction about 76. The bent lug 79 of this lever 75 is disengaged from the notch 80 of the coupling sleeve 73. This sleeve is no more driven and the cam 71 is stopped. The size detection does not take place; and neither does the reversal of the pick-up; the lever 118 holds its position and the pick-up whose stylus is still directed downwards is once more lowered onto the upper side of the record 6 supported on the turntable. If the lever arm 192 is maintained in its position 192', the same series of operations will take place once more, but it will be the extremity 187 of the lever (192—185—187) that will now engage the coupling lever 75 for disengaging the cam 71 from the cam 51.

If however the lever (192—185—187) is brought back into its first position shown in full lines in Fig. 10, the coupling lever 75 will engage the sleeve 73 and the cycle will proceed normally with the detection of the size of the record 12¹, playing of the under side of this record, dropping of said record onto the turntable, etc.

Second case.—Repetition of the under side of the record 12¹ supported on the surface 13 of the shaft 11.

The cycle is at the point where the pin 126 follows the descending ramp 128² of the cam path 128. The lever (192—185—187) is brought into

16

the dotted line position (192—185—187) of Fig. 10. The pin 184 does not more actuate the star wheel 182; the switch 132 remains in the same position, closing the path 129 and taking open the path 128. The extremity 187 of the lever (192—185—187) actuates the coupling lever 75, thus stopping the cam 71 before the path 82 actuates the levers and rods of the record feeding and also before the pin 224 actuates the link 221.

10 The record 12¹ remains in its position on the supporting surface 13 and the pick-up 7 comes once more to play the under side thereof, the stylus 8 being still directed upwards since no reversal of the pick-up has been effected.

15 In the second practical embodiment of the invention shown in the Figures 19 to 31, the general construction of the machine is substantially the same as in the first embodiment; the record feeding device of the changer and the control mechanism thereof are identical; the record size detection device and its control mechanism are also almost identical and do need not to be described again, but for the elements which are necessary to the understanding of the invention and the elements which have been modified in shape or otherwise.

20 The upper motor 16 which drives the removable shaft 11 supporting the stack of records 12 is secured on a bracket being part of a metallic housing 580 secured to the base plate 2 by means of screwed feet 501a, 501b, said housing covering the base of the tone arm, and the members of the record feeding device and of the record size detection device which are situated above the base plate 2 of the machine.

25 On the shaft 4 of the lower motor 1 is fixed, as shown in Fig. 21, the driving pinion 47 with which may be coupled the coupling pinion 48 which constantly meshes with the large diameter gear 49 secured to the shaft 50. As in the first construction, the coupling pinion 48 is put into gear with the driving pinion 47 at the termination of the playing of a record side and put out of gear therefrom before the playing

30 of the subsequent record side. The large diameter gear 49 is riveted to the upper face of a sleeve 252, secured to the shaft 50 by means of a tightening screw 253. On the same shaft 50 is fixed, by means of a cross pin 330 (see Fig. 24), the cam 251 controlling the movements of the tone arm, which cam substantially differs from the control cam 51 of the first construction.

35 On the shaft 4 of the lower motor 1 is fixed, as shown in Fig. 21, the driving pinion 47 with which may be coupled the coupling pinion 48 which constantly meshes with the large diameter gear 49 secured to the shaft 50. As in the first construction, the coupling pinion 48 is put into gear with the driving pinion 47 at the termination of the playing of a record side and put out of gear therefrom before the playing

40 of the subsequent record side. The large diameter gear 49 is riveted to the upper face of a sleeve 252, secured to the shaft 50 by means of a tightening screw 253. On the same shaft 50 is fixed, by means of a cross pin 330 (see Fig. 24), the cam 251 controlling the movements of the tone arm, which cam substantially differs from the control cam 51 of the first construction.

45 The large diameter gear 49 meshes with a gear 62 secured to the shaft 63 of the pinion 64, which latter meshes with a gear 65 riveted to the lower face of a sleeve 66 secured to the shaft 70 by means of a tightening screw 74. On the shaft 70 is fixed the cam 71 controlling the record feeding device, the record size detection device and the reversal of the pick-up. This cam 71 is identical to that of the first construction and is also rotated one half of a revolution while the cam 251 is rotated one full revolution.

50 The shafts 50, 63 and 70 are rotatably supported in the plates 55 and 68 (Fig. 20) which constitute the frame of the mechanism and are fixed to one another by four columns 69 riveted to the plate 68 and secured to the base plate 2 by means of screws 254.

55 The record size detection mechanism only differs from that of the first construction by the shape of the lever 418 (Figs. 22 and 24) corresponding to the lever 118 of the first construction. This lever 418 is pivoted about a pin 419

60 on the lower side of the lower plate 68 and its

65

70

function is identical to that of the lever 418 in the first construction. On its extremity 418', bent at 420, is fixed a pin 300 placed on the way of the extremity 99' of the lever 99 of the feeler; the lever 418 is further provided with a lug 421 placed on the way of a pin 422 fixed to the upper side of the cam 71. At its extremity opposite the pin 300, the lever 418 is formed with two steps, namely the step 423 which is the more distant from the pivot 419 and the step 424 which is the less distant from this pivot. Either steps 423, 424 are adapted to co-operate, according to the position of the lever 418, with the arm 125 being part of the mechanism controlling the movements of the tone arm. The extremity 418' of the lever 418 may be brought into three different positions:

(a) Under the action of the pin 422 of the cam 71 on the lug 421 it is brought into its extreme left hand position.

(b) When the roller 104 of the feeler runs against the edge of a 25 cm. record, the extremity 99' of the lever 99 brings the extremity 418' of the lever 418 into its middle position, in which the arm 125 cooperates with the step 424.

(c) When the roller 104 of the feeler runs on the under side of a 30 cm. record, the extremity 99' of the lever 99 brings the extremity 418' of the lever 418 into its extreme right hand position, in which the arm 125 co-operates with the step 423.

Pick-up control mechanism

The properly called sound reproducing device comprises the single tone arm 520 carrying the pick-up 507 adapted to play successively the under side of the lowermost record 12¹ of the stack 12 supported on the supporting surface 13 of the removable shaft 11 and the upper side of the record 6 supported on the turntable 5. The pick-up 507 is in the shape of a box made of moulded material, for instance of synthetic resin or aluminium casting, and enclosing the oscillating armature carrying the stylus 8 and the device for transforming the mechanical oscillations into electrical oscillations. The sound box 507 carries a hollow shaft 522 rotatably supported within a sleeve 524 secured to the front part 301 of the single tone arm 520 which comprises further two parallel arms 302 and 303 and a base 304. The point of a screw 525 screwed in the front part 301 of the tone arm engages a semi-circular groove 305 on the hollow shaft 522. The groove 305 co-operates with the point of the screw 525 so as to secure the hollow shaft 522 against any axial displacement while allowing a maximum rotation of this shaft through 180°. The screw 525 and the groove 305 determine two definite positions of the pick-up 507 as shown in Fig. 26, namely the full line position 507' with the single stylus 8 directed downwards in the position 8', and the dotted line position 507'' with the stylus directed upwards in the position 8''.

The reversal of the pick-up 507 with respect to the tone arm is brought about by the following device: The extremity 306 of the hollow shaft 522 (Fig. 26) is formed with a pinion which meshes with a bell-shaped bevelled gear 307 riveted to a sleeve 308; the sleeve 308 is rotatably supported by the head 309 of a screw 310 screwed in the front portion 301 of the tone arm. The sleeve 308 is provided with a longitudinal slot 311 adapted to receive a pin 312 when said pin faces said slot. The pin 312 is secured to the semi-

spherical head 313 of a shaft 314 rotatably supported within two sleeves 315 and 316, screwed in a screw threaded hole 317 of the base plate 2 of the machine. The upper end of the shaft 314 is formed with a flange 318 adapted to limitate the downward displacements of this shaft.

On the lower end of the shaft 314 is secured by a screw 319 a sleeve 320 riveted to a sector-shaped plate 321 which is intended at a time as a crank 10 for the rod 221 with which it is hingedly connected at 322 and by its projections 323 and 324 (Fig. 31) as an abutment co-operating with a pin 325 screwed in the base plate 2.

A spring 326 connecting the lower end of the pin 325 and the pivot 322 of the pieces 321 and 221 determines two positions 321^I and 321^{II} (Fig. 31) of the sector 321. The rod 221 is actuated by a pin 224 secured to the lower side of the cam 71 (Figs. 24 and 31). When the cam 71 rotates in 20 the direction of the arrow f² as viewed in Fig. 31, the pin 224 takes successively the positions 224^I, 224^{II}, 224^{III} and 224^{IV}. The travel from 224^I to 224^{II} causes the rod 221 to pass from the position 221^I to the position 221^{II} and the sector 321 to pass 25 from the position 321^I to the position 321^{II}. The shaft 314 is thereby rotated through an angle α , as indicated in Fig. 31. When the pin 312 engages within the slot 311 of the sleeve 308, the latter is also rotated through the same angle α 30 and this rotation is transmitted through the bevelled gear 307 and the pinion 306 to the pick-up 507. The angle α and the gear ratio of the bevelled gear 307 to the pinion 306 are chosen so that the travel of the pin 224 from 224^I to 224^{II} 35 determines a clockwise rotation through 180° of the pick-up 507 which brings the stylus 8 from the position 8' to the position 8'' as shown in dotted lines in Fig. 26. On the other hand, the travel of the pin 224 from 224^{III} to 224^{IV} determines a counter-clockwise rotation through 180° of the pick-up 507 which brings the stylus 8 back to the position 8'. The movements of the pick-up 507 during the cycle of the record changer are as follows: During the playing of the upper side of the 40 record 6 supported on the turntable 5, the pick-up occupies the position 507^I (Fig. 23). At the termination of the playing of this record side, the pick-up is lifted above the record 6 and is brought into the position 507^{III}, intermediate between the record 6 and the record 12¹ supported on the surface 13 of the shaft 11. The pick-up is then moved outwards into the position 507^V (Fig. 19), where the sleeve 308 is in vertical alignment with the shaft 314. The pick-up is then lowered to the position 507^{IV} where the base of the sleeve 308 bears against the flange 318 and the pin 312 faces the slot 311 and penetrates thereinto. The pick-up is then reversed as hereinbefore described and lifted again into the intermediate position 507^{III} 45 with the stylus 8 directed upwardly. The pick-up is moved inwards until the stylus comes into vertical alignment with the outer groove of the record 12¹ and lifted for playing the underside of this record. At the termination of the playing of the underside of the record 12¹, the pick-up is first 50 lowered to the intermediate position 507^{III}, then moved outwards into the position 507^V, and lowered into the position 507^{IV} where the pin 312 faces again the slot 311 and penetrates thereinto. The pick-up is then reversed as hereinbefore described and the stylus 8 is thus directed 55 downwardly for playing the upper side of the record supported on the turntable 5.

This second embodiment presents the following 75 advantages: The pick-up 507 may be reversed

manually at any desired time, except during the automatic reversal, from one to the other playing position without disturbing the cycle of the changer. When in fact the pick-up 507 is being reversed manually while occupying any position except the position 507^V, the sleeve 308 is driven in rotation through an angle α by the gear 307 and the pinion 306. As then the normal automatic reversal occurs, the pick-up is brought into the position 507^V, as however the slot 311 has been rotated through the angle α without the pin 312 being simultaneously displaced, the pick-up bears by the base of the sleeve 308 (Fig. 29) on this pin 312 and when the latter is in turn rotated through the angle α under the action of the cycle control mechanism, it does not drive the sleeve 308; the pick-up which was already occupying the reversed position remains there for playing the subsequent record side. The pick-up 507 may further be reversed manually while in either of the positions shown in Fig. 26, except during the automatic reversal. In fact the pin 312 is driven in rotation by the slot 311 and drives in turn the rod 221 which is adapted to pass from one to the other of its position owing to the elongated aperture 223. That will occur while the changer is stopped at the end of the playing. The pin 224 occupies then the position 224^{VI} shown in Fig. 31.

The reversal of the pick-up does not produce any strain on the pivoting means thereof. Owing to the semi-spherical end 313 of the shaft 314 engaging within the sleeve 308, the pick-up is secured against any lateral displacement; furthermore owing to the sides of the slot 311 forming an angle β (Fig. 28) with one another, the pin 312 will lock the pick-up against any lifting with the result that the pick-up which is essentially movable and light while in playing position, constitutes during the automatic reversal a rigid unit together with the frame of the changer without its pivoting means being subjected to any supplemental strain.

The movements of the tone arm 520 which carries the pick-up 507 are controlled by the cam 251 secured to the shaft 50 by the pin 330. The cam 251 is provided on its upper side with the cam path controlling the inward and outward movements of the tone arm; as shown in the Figures 22 and 24, a lever 331 pivoted about a pin 332 secured to the underside of the lower plate 68, carries a pin 333 on its underside. This pin 333 is guided by the outer side wall 334 of a path 335 against which it is resiliently held by a spring 336 attached on the one hand to the lever 331 and on the other hand to a pin 337 secured to the underside of the plate 68. The lever 331 is hingedly connected at its extremity 331' with a link 338 by means of a rivet 339, a sleeve 340 and a washer 341; the sleeve 340 is adapted for free sliding movement within an elongated aperture 342 of the link 338. A spring 343 tends to hold the sleeve 340 against the extremity 342' of the aperture 342.

The link 338 is hingedly connected at its other extremity 338' with a lever 347, by means of a pin 344, a sleeve 345 and a washer 346. The lever 347 has a rectangular aperture 348 and is pivoted about a screw 349 through the medium of a sleeve 350 riveted to the lever 347. The screw 349 is screwed to the base plate 2 of the machine. The lever 347 may occupy three distinct positions:

1. Position for playing a 30 cm. record. The arm 125 of the lever 347 contacts the surface 423 of the lever 418 against which it is urged under in-

fluence of the spring 336. The edge 351 of the aperture 348 has brought the pin 352 dependent upon the tone arm into the position 352^I in which the stylus 8 is in vertical alignment with the outer groove of a 30 cm. record.

2. Position for playing a 25 cm. record determined by the surface 424 of the lever 418.

3. Position for the reversal of the pick-up 507.

The edge 353 of the aperture 348 has brought the pin 352 into the position 352^{II} corresponding to the position 507^V of the pick-up. This position 352^{II} is determined by an adjustable stop 354' constituted by the one extremity of a piece 352 secured to the base plate 2, by a screw 355. 15 When the pin 333 is brought into the position 333^I by the cam path 335, the spring 343 urges the pin 352 against the stop 354' through the medium of the link 338 and of the edge 353 of the aperture 348.

20 The tone arm 520 (Fig. 23) is pivoted by its base 304 about a horizontal pin 457 secured to the two legs of a stirrup 456. Two lugs 454 and 455 of the same stirrup carry two screws 452, 453 having tapered points 450, 451 and locked by two lock-nuts 363, 364. The tapered points of the screws engage tapered holes provided in corresponding lugs of a U-shaped piece 449. The tapered points 450, 451 constitute the pivots of the vertical axis of rotation of the tone arm. 30 The U-shaped piece 449 is welded to an upstanding bracket 365 secured to the base plate 2 by means of two screws 366 and 367.

The lateral movement of the tone arm 520 about this vertical axis are controlled in playing position of the pick-up 507 by the sound grooves of the record. During the record changing operations these movements are controlled through the medium of the pin 352 secured to the lower end 356 of an arm 357 fixed by two screws 359, 360 to the stirrup 456. The pin 352 is actuated as hereinbefore described by the edges of the aperture 348 of the lever 347.

The upward and downward movements of the tone arm 520 are brought about as follows: In 45 the bent upper extremity 358 of the arm 357 there is rotatably supported a pin 368 secured to a semi-circular pulley 362 having a peripheral groove formed between two jaws 370 and 371 (Figs. 19 and 23). This pulley receives in its 50 groove the one extremity of a coil spring 372 attached on the one hand to the pulley at 372 and on the other hand to a cross plate 374 connecting the two arms 302 and 303. Furthermore there is a cable 375 attached to the pulley 362 through the medium of a screw 376 having a diametrical bore 377. The cable 375 leaves the pulley opposite the spring 372, passes through an aperture 378 of the base 304 of the tone arm, passes further through the axially bored screws 60 452 and 453, then through an aperture 380 of the base plate 2 and has its other extremity attached to the extremity 379' of a bell crank 379 (Fig. 25) positioned underneath the base plate 2. According to the position taken by the bell crank 65 379, the pick-up 507 works at different levels:

1. The bell crank 379 occupies the position 379^I. The cable 375 and the spring 372 are dimensioned so that the spring 372 is in fully un tensioned condition when the pick-up 507 70 bears by its stylus 8 on the first record 6 supported on the turntable 5. The pick-up rests thus by gravity on said record 6. As further records drop onto the record 6, the pick-up follows the progressive raising of the playing level 75 by rotating about the horizontal pin 457.

21

2. The bell crank 379 occupies the position 379^{III}. The pick-up is lifted through the medium of the cable 375 and of the spring 372 to the level 507^{III} adapted for the outward movement of the tone arm.

3. The bell crank 379 occupies the position 379^{IV}. The pick-up is lowered to the corresponding level 507^{IV}.

4. The bell crank 379 occupies the position 379^V. The pick-up, hanging by the cable 375 and the spring 372, which latter is tensioned by the weight of the pick-up is lifted to such a level that the upward directed stylus 8 contacts the underside of the record 12¹ supported on the surface 13 of the shaft 11.

5. The bell crank 379 occupies the position 379^{VI}. The additional travel from 379^V to 379^{VI} gives the spring 372 an implement of tension which presses the stylus 8 against the record 12¹ with the pressure necessary to a correct reproduction.

The different positions of the bell crank 379 are determined by the cam paths provided on the underside of the cam 251 (Fig. 24). The bell crank 379 is pivoted by means of a rivet 385 and a washer 386 on the downward extending arm 382 of a bracket 381 secured to the underside of the base plate 2 by two screws 383, 384. At the extremity 379^{II} of the bell crank 379 there is hooked the one end of a link 387 the other end of which is hooked to the extremity 388 of a bell crank 380 bent at 389 and pivoted about the end 392 of a column 393 screwed to the underside of the plate 68. The opposite extremity of the bell crank 380 carries a pin 391 which follows the cam paths on the underside of the cam 251 to control the movements of the bell crank 379. These cam paths present a series of differently directed portions: A is a cam path portion concentric to the axis of the cam 251 and corresponds to the position 379^I of bell crank 379; the pick-up 507 is playing the upper side of a record supported on the turntable 5. Cam path portion B causes bell crank 379 to pass from 379^I to 379^{III}. Cam path portion C is concentric to the axis of cam 251 and corresponds to the position 379^{III} or bell crank 379; the pick-up is at the level adapted for outward movement of the tone arm. Cam path portion D causes bell crank 379 to pass from 379^{III} to 379^{IV}. Cam path portion E is concentric to the axis of cam 251: the pick-up is at the level adapted for reversal thereof. Cam path portion F causes bell crank 379 to pass from 379^{IV} to 379^{III}. Cam path portion G is concentric to the axis of cam 251 and corresponds to the position 379^{III} of bell crank 379 and to the intermediate level of pick-up 507. Cam path portion H causes bell crank 379 to pass from 379^{III} to 379^{II}. Cam path portion I is concentric to the axis of cam 251; bell crank 379 is in the position 379^{II} and pick-up 507 in position for playing the record 12¹. Cam path portion J causes bell crank 379 to pass from 379^{II} to 379^{III} again. The pin 391 follows then again the cam path portions C, D, E, F, and G. Cam path portion K causes then bell crank 379 to pass from 379^{III} to 379^I, thus completing the operative cycle of the pick-up 507.

The switch 394 is operated upon completion of each revolution of cam 251, thus alternately opening the cam path portions H and K for the pin 391 to pass. Switch 394 is pivoted about a pin 395 riveted to the cam 251. The switch 394 is provided beyond the pin 395 with an extension 396 ending in a vertically extending cylindrical shank 397 passing through the whole cam 251

22

through an aperture 398 thereof. On the upper side of cam 251, this cylindrical shank 397 engages the forked extremity of a lever 399 pivoted about a screw 400 secured to the cam 251 (Fig. 22).

5. The lever 399 is provided with a bent lug 401 extending downwardly within a recess 402 of cam 251. Within said recess 402 there is also a cam 403 dependent upon a star wheel 404; this cam and star wheel assembly is pivoted about a screw 405 fixed to the cam 251. A thread-like spring 406 fastened to the cam 251 by a screw 407 urges the lug 401 against the cam 403. At each passage of the star wheel 404 in front of a pin 408 secured to the underside of the plate 68 (Figs. 21 and 24) the said star wheel is rotated through one fourth of a revolution. The cam 403 rotates through the same angle and actuates the lug 401 of lever 399 thus swinging the switch 394.

10. The operative cycle of the changer is as follows:

1. At the termination of the playing of the upper side of the record 6 supported on the turntable 5, the eccentric terminal groove of this record imparts to the stylus 8 and hence to the pick-up 507 a sudden impulse which is transmitted by the tone arm 520 through the arm 357 and the pin 352 to an automatic stop device (not shown) which brings the coupling pinion 48 into gear with the driving pinion 47. The cam 251 begins to rotate in the direction of arrow f¹ and the cam 71 in the direction of arrow f².

2. The lower control pin 391 which was positioned during the playing of the upper side of the record 6, on the portion A of the cam path 409, is now following the cam path portion B. The pick-up is lifted to the level 507^{III}. Meanwhile the pin 408 rotates the star wheel 404 one step thus swinging the switch 394 to close the inlet of the cam path portion K and open that of the portion H.

3. The upper control pin 333 (Fig. 22) follows the portion L of the cam path 335 thus retracting the tone arm and bringing the pick-up into its reversal position 507^{IV} beyond the periphery of the records, in which position the sleeve 308 is in vertical alignment with the shaft 314. The spring 343 takes up the surplus of the travel of the guiding pin 333 after the pin 352 has contacted the abutment 354'. The same spring 343 is also tensioned when the pick-up is retained manually against its outward movement, thus preventing any deterioration of the mechanism.

4. The lower control pin 391 follows the portion D of the cam path 409 thus lowering the pick-up to the reversal level 507^{IV}.

5. Meanwhile the cam 71 which controls the record size detection, the record feeding mechanism and the reversal of the pick-up has rotated one-fourth of a revolution. The pin 422 has actuated on its way the lug 421 of the lever 418 thus bringing the pin 300 into its extreme left hand position. The cam path 83 co-operates with the roller 84 of the feeler to detect the size of the record 12¹ as described in connection with the first embodiment of the invention, thus finally bringing the lever 418 into the position corresponding to the size of the record 12¹.

6. Simultaneously, the pin 224 of cam 71 brings the link 221 from the position 221^I to the position 221^{II} whereby the pick-up 507 is reversed to direct the stylus 8 upwardly.

7. The lower control pin 391 follows the cam path portion F, thus lifting the pick-up to the level 507^{III}.

8. The upper control pin 333 follows the cam

path portion N under influence of spring 336, thus moving the lever 347 until the arm 125 comes in contact with the suitable surface 423 or 424 of lever 418. The stylus 8 is then in vertical alignment with the outer groove of the record 121.

9. The lower control pin 391 follows the cam path portion H and reaches to the point I thus lifting the pick-up to bring the stylus 8 into contact with the underside of the record 121 and tensioning the spring 372 to secure the upward pressure necessary to the correct reproduction of this record side.

10. The coupling pinion 48 is retracted from the pinion 47 thus stopping the whole mechanism of the changer during the playing of the underside of the record 121.

What I claim is:

1. A talking machine with record changer and sound reproducing device adapted to play in succession the underside of the lowermost record of a stack supported on first supporting means and the upper side of the same record after it has been brought without reversal onto second supporting means positioned in vertical alignment with said first supporting means, comprising a frame, a simple tone arm pivotally mounted on said frame for movements in both horizontal and vertical planes between said first and second record supporting means, a pick-up having a single stylus mounted at the free end of said tone arm for pivotal movement through 180 degrees about an axis situated in alignment with said tone arm, means for controlling the cycle of the record-changer, first coupling member supported by said frame and second coupling member carried by said tone arm for periodically coupling said pick-up with said cycle control means when said tone arm is in a predetermined position thereby to promote rotation of said pick-up with respect to said tone arm so as to direct said single stylus toward either said first or second record supporting means.

2. A talking machine as claimed in claim 1 wherein each of the coupling members is rotatably mounted about a shaft supported by the machine frame and by the tone arm respectively, both said shafts being so arranged as to be brought into mutual alignment for reversing the pick-up by a movement of the tone arm.

3. A talking machine as claimed in claim 1, wherein each of the coupling members is rotatably mounted about a shaft supported by the machine frame and by the tone arm respectively, both said shafts being so arranged as to be brought into mutual alignment for reversing the pick-up by a movement of the tone arm in a substantially horizontal plane intermediate between the first and second record supporting means.

4. A talking machine as claimed in claim 1, wherein each of the coupling members is rotatably mounted about a shaft supported by the machine frame and by the tone arm respectively, both said shafts being so arranged as to be brought into mutual alignment for reversing the pick-up by a movement of the tone arm in a substantially vertical plane.

5. A talking machine as claimed in claim 1, where in the first coupling member is rotatably mounted about a shaft supported by the machine frame, said shaft being in alignment with the axis of rotation of the pick-up when said pick-up is in the predetermined reversal position, the second coupling member being rigidly secured to the pick-up, and means being pro-

vided for directly transmitting the rotative movements of said first coupling member to said pick-up when said first and second coupling members are in mutual engagement.

5 6. A talking machine as claimed in claim 1 wherein gearing means are provided between the second coupling member rotatably carried by the tone arm and the pick-up for turning the pick-up over through 180 degrees when said coupling member is rotated through a fraction of 180 degrees.

10 7. A talking machine as claimed in claim 1 comprising interengaging abutment means on the tone arm and on the pick-up for limiting the rotation of the pick-up to 180 degrees, and movement transmission means to rotate alternately the pick-up in the opposite directions from one playing position into the other playing position.

15 8. A talking machine as claimed in claim 1 wherein the first and second coupling members are provided with means for locking the tone arm against any movement with respect to the machine frame during the reversal of the pick-up.

20 9. A talking machine with record changer and sound reproducing device adapted to play in succession the underside of the lowermost record of a stack supported on first supporting means and the upper side of the same record after it has been brought without reversal onto second supporting means positioned in vertical alignment with said first supporting means, comprising a frame, a simple tone arm pivotally mounted on said frame for movements in both horizontal and vertical planes between said first and second supporting means, a pick-up having a single stylus rigidly secured to a shaft rotatably supported in the free end of said tone arm for pivotal movement through 180 degrees about its axis situated in alignment with said tone arm, said pick-up carrying shaft having its inner end formed with a pinion, a bevelled gear meshing with said pinion, and rigidly secured to a sleeve having a longitudinal slot therein and rotatably mounted on a second shaft secured to said tone arm perpendicularly to said pick-up carrying shaft, a third shaft rotatably supported by said machine frame in a substantially vertical position beyond the periphery of the records and having its upper spherical end provided with a radial pin and adapted to engage within said sleeve with its radial pin operatively engaging in said slot thereof when said tone arm is in a position corresponding to the reversal position of said pick-up, rotatory means for controlling the cycle of the record changer and means for periodically transmitting rotatory motion from said cycle control means to said third shaft, whereby rotatory motion is transmitted to said pick-up carrying shaft by means of said interengaging pin and slot and intermeshing bevelled gear and pinion to direct said single stylus toward either said first or second record supporting means.

25 10. A talking machine as claimed in claim 9 wherein the sides of the longitudinal slot in the sleeve are arranged at an angle to each other, the apex of said angle being directed toward the open side of said sleeve, said tapered slot operatively cooperating with the radial pin on the spherical upper end of the third shaft for axially locking said sleeve during the reversal of the pick-up.

30 11. A talking machine as claimed in claim 9

wherein the means for transmitting rotatory motion from the cycle control means to the third shaft comprise a crank and rod system operatively engaging a lever secured to said shaft, said rod being formed with an elongate aperture for said crank whereby only a fraction of the available stroke of said rod is needed for turning the pick-up through 180 degrees by a rotation of said crank inferior to 180 degrees, and according to the angular position of said crank, said third shaft is allowed to be turned manually without said crank being moved.

12. A talking machine as claimed in claim 9 wherein the gear ratio of the intermeshing bevelled gear and pinion is such that the sleeve rotates through less than 360° for a 180 degrees rotation of the pick-up, whereby the radial pin is allowed to enter the longitudinal slot for only

one predetermined angular position of the pick-up included within said 180 degrees rotation.

LOUIS THÉVENAZ.
